UNITED STATES PATENT OFFICE

HENRY W. DAVIDSON, OF LANCASTER, OHIO

DESIGN FOR A STREET LIGHT GLOBE

Application filed July 7, 1931. Serial No. 40,443. Term of patent 3½ years.

To all whom it may concern:

Be it known that I, HENRY W. DAVIDSON, a citizen of the United States, residing at Lancaster city, in the county of Fairfield and State of Ohio, have invented a new, original, and ornamental Design for a Street Light Globe, of which the following is a specification, reference being had to the accompanying drawing, forming part thereof.

Figure 1 is a side elevation of a street light globe showing my new design; and Figure 2 is a top plan view on somewhat of a reduced scale.

I claim:

The ornamental design for a street light globe as shown.

HENRY W. DAVIDSON.
